Primary Examiner — Darlington Ly(74) *Attorney, Agent, or Firm* — John Alumit(57) **CLAIM**

The ornamental design for a saw blade as shown and described.

DESCRIPTION

FIG. 1 is a top view of a saw blade embodying my new design;

FIG. 2 is a bottom plan view thereof;

FIG. 3 is a side elevation view thereof;

FIG. 4 is a bottom and side perspective view thereof;

FIG. 5 is a bottom and opposing perspective view thereof;

and,

FIG. 6 is an enlarged and partial top plan view thereof, wherein the enlarged area is identified as boundary 6 in FIG. 1.
